UNITED STATES PATENT OFFICE.

JOSEPH BETHENOD, OF PARIS, FRANCE, ASSIGNOR TO MOTOR INDUSTRIES, INC., OF CHICAGO, ILLINOIS, A CORPORATION OF ILLINOIS.

MEANS OF DECLUTCHING.

Application filed August 5, 1926, Serial No. 127,471, and in France August 7, 1925.

The object of my invention is to realize a simple device which automatically produces the disengaging of the clutch of a motorcar, or the like, as soon as the throttle 5 pedal is released.

It is in this way possible to obtain a very important fuel saving, which is evident to any automotive engineer.

This device consists in producing the disengaging by means of a vacuum servo-motor, which is connected for example to the inlet manifold of the motor of the car. This servo-motor acts on the clutch as soon as the throttle pedal is released; this result 15 is obtained by means of a distributing valve, or the like, which controls the degree of vacuum.

The figure shows a form of my invention as applied to a cone clutch 1. According 20 to a known disposition, the clutching is effected by means of a spring 2, and the de-clutching is obtained when depressing a foot-pedal 3, which acts by means of a lever 4. The vacuum motor comprises a cylinder 25 5, in which slides a piston 6 which is connected up to the lever 4 by means of a rod 7. A pipe 8 connects the cylinder 5 up to the distribution valve 9, which is communicating with the inlet manifold of the motor 30 by means of another pipe 10. Further, the movement of the pistons of the valve 9 is controlled by the throttle pedal 11, which acts on the throttle by means of the rod 12.

This device operates as follows:

35 When the motor is idle, the cylinder 5 communicates with the inlet manifold of the motor, as shown on the figure. Hence the piston 6 pulls on the rod 7, and the clutch 1 is thrown out. As soon as the pedal 11 40 is depressed, the communication between the cylinder 5 and the inlet manifold is interrupted by the piston 13, and the former communicates with the atmosphere through the orifice 14. Then the clutch 1 is thrown 45 in.

Sometimes, the piston valve 9 can be supplied by a single valve, which obstructs an orifice as long as the pedal 11 is released. Besides a cock, or the like, can be added in order to suppress the action of the device, 50 when, for example, the car is going down a hill.

The motor can thus act as a brake, as well known. It will be noticed that when the clutch is sufficiently progressive this arrangement dispenses with any foot operation on the usual clutch pedal, when starting.

A dash-pot can be added in order to increase the progressivity of the clutching.

Finally, it is obvious that the vacuum 60 servo-motor can be supplied for example by an electrical servo-motor fed by means of the storage battery of the car.

In such a case, the operation of the device remains the same as above, the piston 65 valve being naturally supplied by a switch.

Having thus described my invention, what I claim as new and desire to secure by Letters Patent is:

Automobile controlling mechanism includ- 70 ing a clutch pedal, an accelerator, and an intake-manifold connection, in combination with a suction-operated device acting on the clutch pedal, and a valve for connecting said device to the intake-manifold connec- 75 tion and which is connected to the accelerator and which includes a cylinder and a double-piston valve in the cylinder, the space between the piston portions of said valve being in alignment with the intake-manifold 80 connection and with the connection to said device when the accelerator is released, and with one of the piston portions of said valve arranged between the intake-manifold connection and the connection to said device 85 when the accelerator is operated.

JOSEPH BETHENOD.
